COMBINED SCORE CARD AND MEMORANDA
BOOK

Mildred L. Lemburg, Fullerton, Calif.

Application October 26, 1935, Serial No. 46,916

6 Claims. (Cl. 231—1)

This invention is a notation or memoranda device in the nature of a combined pocket book and score card.

An object is to provide a book with one or 5 more pages of forms including memoranda lines and suitable indicia or indexes therefor, in combination with a foldable back or cover capable of being opened out flat to present a good size area for the ready display of the indicia sheets, and 10 in combination with a plurality of writing windows, all so constructed and arranged as to be folded to a very compact condition of a size to be readily, conveniently and un-noticeably carried in the pocket of a piece of wearing material, or woman's purse if so desired.

A further object is to provide a device of this class in which the writing windows have but a quarter of the inner face area of the back or cover and in which the index sheet is an oblong 20 which is twice the area of the window element, and in which the back is a square whose sides are substantially equal to the length of the index sheet; all being so constructed and arranged as to provide for the utilization of either face of 25 the index sheet as a guide for making entries on the inscription face of the writing window.

The invention consists of certain advancements in the method and apparatus of this art as set forth in the ensuing disclosure and having, with the above, additional objects and advantages as hereinafter developed, and whose manner of operation and construction, combination and means, and details of features will be made manifest in the description of the herewith 30 disclosed and illustrative embodiment; it being understood that modifications, variations and adaptations may be resorted to within the scope, principle and spirit of the invention as it is more directly claimed hereinbelow.

40 Figure 1 is a perspective of the device in open position; a half of one sheet being out-turned to show manipulation of the parts.

Figure 2 is an edge view of the compacted or closed book.

45 Figure 3 is a sectional perspective of a hold-down tab.

Figure 4 is a plan of an example of a game card imprinted on one of the book sheets.

50 Figure 5 is an enlarged detail of one of the indexed play record spaces of a score card.

The cover or back 2 preferably consists of a single, square piece of durable flexible material, such as leather, or its substantial equivalent, to form enough backing to sustain applied indicia sheets 3, which are oblongs of about one-

half the inner face area of the back 2. The sheets 3 are detachably attached to the vertical center-line of the back by any suitable or desired fasteners 4 and are medially foldable, vertically, to form squares of about a quarter sectional area of the back.

The back is itself designed and constructed so as to be folded on its vertical center-line to bring the right hand quarter sections over the inner face of the left hand sections, and then 10 the lower section at the left, Fig. 1, is folded up over the upper left section to compact the whole as is shown in Fig. 2. The vertical edges of the back have inturned laps 8 and these are split or cut out at 5 to facilitate the folding of the 15 upper halves of the book either with the inner faces face to face, or the outer faces back to back.

In order to preserve the indicia pages or sheets 3 for repeated use a feature of the invention resides in the provision of a set of four equi-sized transparencies 6, which are substantially quarter-sections in area of the inner face of the back 2; the outer surfaces being sufficiently abraded to receive pen or pencil notations which may be 20 readily erased at will. The members or writing windows 6 are water-proof and form firm surfaces, but have a desirable degree of flexibility; celluloid being especially adaptable.

Each of the writing windows is suitably attached along its outer vertical edge, as by stitching 30 7, to the overlapped margins 8 of the back 2. This leaves the inner-most edges of the windows 6 free and lying close to the vertical axis of the book of sheets 3, of which any suitable number may be used.

Suitable retainers are provided to releasably hold down the free inner corners of the windows 6. As here shown, at the top and bottom of the vertical diameter of the back there are provided 40 tabs 9, preferably of triangular form, medially stitched at 10 to the back and thus forming small pockets into which may be tucked the adjacent corners of the windows 6. At the intersection of the vertical and horizontal center-lines of the back 2 there is stitched, or otherwise attached, a square pad 11, with its edges diagonally arranged on the back and forming four pockets for the four innermost corners of the windows 6. The tabs 9 and the pad or patch 11 are made 45 of flexible material to provide for the folding of the cover sections.

It will be seen that when the back is opened out flat to present the sheets or leaves 3, the presented faces are covered by the writing windows 55

6. The front and back of each page of each sheet 6 may be provided with any desired indicia and column or line forms, according to the character 10 of record to be kept; the memoranda being entered on the face of the writing window, for later transfer to a permanent record as desired. Either face of any page (one-half of a sheet 3) may be presented by merely turning it to a position under either relative writing window. To 15 provide for this without interference by the retainers 9-11, the centers of the top and bottom edges of the leaves, Fig. 4, are notched out at 12 to clear the retainers as the page part is turned, as shown in Fig. 1, after its covering window, at 20 the right, for instance, has been released from its retainers. The window under which the page is to be laid is then pulled from under its corner retainers and the free page is lapped down to place and the desired window is again laid down 25 and tucked under its retainers.

The device is especially useful for the keeping of a temporary score or tally of a desired game or contest and in Fig. 4, there is shown a preferred form of score card for a base-ball game in which 25 imprinted indicia and relative spaces are provided for the guidance of an entry on the face of the overlapped writing window.

A feature of this score card consists of an index comprising a quadrangle, Fig. 5, including a 30 home-plate mark 15 and the base numerals "1", "2", "3" disposed in the usual form of a base-ball diamond. A letter "H" in the left field area indicates a home run by a player. During each 35 inning of a game the person keeping the score, scribes in the quadrangle 14, a line from the home plate mark to the base marks gained by a player. The remaining symbols of the base-ball score card are conventional and well known; but their arrangement here is distinctive and unique.

40 The word "card" as used herein means an imprinted, or otherwise made, surface on which is displayed a chart for any given game in which opposing parties or teams are matched, or a surface of other indicia and notation forms.

45 What is claimed is:

1. A combined memoranda book comprising a back of rectangular form and which is foldable on its center-lines to form a pack of about one quarter of the area of the face of the back, and a pair 50 of cards which together about equal the size of the back; the cards being provided on respective half-sections of the back so as to lie in plain view when the back is opened flat and an independent,

quarter-section, writing window for each quarter section card part.

2. A device as set forth in claim 1, and in which each card is an oblong of about one-half of a face area of the back and is detachably secured 5 to a center-line of the back and is foldable on its own minor axis when the back is closed; one card being on one half and one on the other half of the back.

3. A memoranda book comprising a back of 10 square form which is foldable to form a square pack of about one quarter of the area of the face of the book back, a pair of score cards on and each covering about one-half of the inner face of the back and being medially attached to the 15 vertical center-line of the back, one on the upper half and one on the lower half of the back, and writing windows each covering about one-half of each card and affixed to the back and having an outer face providing for entry and erasure of play 20 feature records of the game indicated on the score cards.

4. A device as set forth in claim 3, and in which said windows are secured to the back alone on one edge only of each window; whereby the end 25 halves of each score card may, at will, be folded from one position to another under either of its respective windows.

5. A memoranda book comprising a back of suitable form and which is foldable into a pack of 30 about a quarter section size of the back and is readily bendable on its center-lines to provide for ready folding of its sections, writing windows about covering each quarter section of the inner face of the back and being secured, each, along 35 one of its edges to the back, indicia sheets each of about the area of one half of the inner face of the back and being secured along its minor axis to the back, both on the vertical center-line of the back, and quarter section writing windows 40 affixed to respective sections of the back and having free inner edges adjacent to the minor axis of the relative, extended sheet; whereby the free halves of the sheets may be turned to underlie either of the windows covering its area of the 45 back.

6. A device as set forth in claim 5, and having means for releasably retaining the free end corners of the windows to hold them close to the indicia sheets and to facilitate notation on the 50 windows.

MILDRED L. LEMBURG.
